JOHN L. RICH, OF OTTAWA, KANSAS

APPARATUS FOR CUTTING CHANNELS IN THE EARTH

Application filed April 19, 1927. Serial No. 185,053.

This invention relates to the recovery of hydrocarbons, and is more particularly directed to an improved method and apparatus for extracting petroleum from underground strata.

In my co-pending application (Serial No. 139,723, filed October 5, 1926), of which this application is a continuation in part, I have disclosed an improved process and means for extracting petroleum from underground strata, which have not been quite "exhausted" by the more common system of wells and pumps employed in the recovery of hydrocarbons. In accordance with the invention 10 therein disclosed, drainage channels are formed through the oil-bearing strata between shafts or working tunnels, by boring drill holes between the shafts or working tunnels, threading cutting ropes through 15 such drill holes and cutting drainage channels therewith in the oil-bearing stratum.

According to the present invention, drainage channels are cut through oil-bearing strata from a single shaft or working tunnel. 20 Holes are bored, preferably just above the oil-bearing stratum, laterally away from the shaft or working tunnel, after which the drainage channels are cut down from these 25 holes through the oil-bearing stratum by a revolving means made to exert an abrasive, or wearing, action on the stratum.

My present invention also contemplates an improved petroleum mining system. The aforementioned drainage channels are cut 30 laterally, from a single shaft or working tunnel. A given project may, however, have a plurality of such shafts from each of which a plurality of lateral drainage channels are cut. In this way the drainage channels may or 35 may not be made to intersect one another. In the case of the use of working tunnels, a plurality of lateral drainage channels may be cut substantially parallel to one another through the oil-bearing strata.

40 This invention also contemplates the provision of a method and apparatus for sealing the entrance to the drainage channels in such manner as to prevent the free escape into the shafts or working tunnels of hydrocarbon gases and vapors formed therein dur-

ing the cutting operation. This is done to prevent explosions and fires, to facilitate ventilation of the shafts and tunnels, and also to recover the gases and vapors.

In accordance with the present invention, 55 a shaft may be run down to or just above an oil-bearing stratum which it is desired to mine in order to recover the valuable hydrocarbons. This shaft is large enough to permit workmen to descend and work in the 60 same. A pit, of somewhat smaller cross-dimension than the shaft, may then be sunk down through the oil-bearing stratum. A lateral hole is next bored through or above the stratum by any well known method. An 65 abrasive-cutting means, such as a pipe-like member having an abrasive outer covering, is pushed into the bored hole. This cutting member is in turn connected with operating means fitting into the mouth of the pit. This 70 operating means comprises a movable platform adapted to be moved up and down the pit on screws, and along fixed posts which allow for a sliding action. The cutting member within the bored hole is operated 75 from a source of power located at a convenient distance. This power is preferably relayed to the operating means in the pit by means of a belt and pulley arrangement. As the cutting member is made to revolve, it 80 gradually grinds or eats its way down through the oil-bearing stratum to form a drainage channel. No additional downward force is applied to the abrasive-cutting member other than that supplied by its own 85 weight. That is to say, the cutting member is allowed to lie freely within the channel as it is made to revolve. As the oil drains from the channels into the bottom of the pit, it may be continuously or periodically withdrawn to the surface above. It is preferred 90 that the entrance to the drainage channel and the pit be sealed to prevent the free escape of gases and vapors from the oil-bearing stratum into the shaft.

95 The aforementioned, and other, features of my invention will be better understood by reference to the accompanying drawings, taken in conjunction with the following description, in which:

Fig. 1 is a conventional cross-section in part of oil-bearing and adjacent strata illustrating an arrangement for practicing the invention;

5 Fig. 2 is a section in part on the line 2—2 of Fig. 1;

Fig. 3 is a diagrammatic ground plan showing one arrangement of shafts, working tunnel, and drainage channels;

10 Fig. 4 is a diagrammatic ground plan showing a modified arrangement of a shaft and drainage channels;

15 Fig. 5 is a plan section of apparatus employed in the shaft or pit to cut the drainage channels;

20 Fig. 6 is a vertical cross-section of oil-bearing and adjacent strata showing the drainage channel cutting apparatus and means for closing the shaft against escape of gases and vapors;

25 Fig. 7 is a cross-section of a means adapted to give the revolving abrasive action necessary to cut the drainage channels; and

Fig. 8 is a transverse section in part on the 25 line 8—8 of Fig. 7.

30 A shaft or tunnel 10 extends down through the upper strata of earth 11 to the oil-bearing stratum 12. A pit 13, of somewhat smaller cross-dimension than that of the shaft or tunnel, extends from the bottom of the shaft or tunnel through the oil-bearing stratum. This pit is sufficiently large to contain the platform 14 in its upward and downward movements.

35 The mechanism for operating the abrasive-cutting means rests upon the platform (see Fig. 5 for details). This mechanism consists of a hollow shaft 15 resting in the bearings 16 and 17 attached to the platform. A pulley-sheave 18, appropriately attached to the shaft, is connected to a source of power (not shown) by means of the belt or rope 19. The source of power may be any suitable engine, preferably located close by. An engine operated by compressed air, and located in the shaft or tunnel, would serve the purpose very well. Particularly in the case of deep shafts, it is preferred not to have the engine located on the outside surface because of its inconvenience and loss of efficiency in transmission of power to the pit below. It is also advisable to have the bearings of the thrust type to counteract any tendency of the abrasive-cutting means to push toward or away from the platform.

40 The platform is kept in a straight up and down line of movement by means of the four supporting posts 20, 21, 22 and 23 which rest within the pit. In order to make the sliding action of the platform up and down the sides of these posts more easy, lugs 24, 25, 26 and 27 are attached to the platform, slidably adjacent to the supporting posts respectively.

45 An additional supporting post-member 28 may be provided within the pit, opposite to

the side into which the channel is to be cut, to counteract any thrust tendency of the platform in that direction when the abrasive-cutting means are put into operation.

50 The platform and its load are supported within the pit by means of the screws 29 and 30 which extend down through the pit. These screws operate within the threaded shoulders 31 and 32 attached to the platform,—so that when the screws are turned, the platform can be moved up or down as desired.

55 The shaft has a connection 33 at one end thereof suitable for making connection with the abrasive-cutting means 34. The other end of the shaft is connected to a flexible conduit 35, such as a hose, by means of a swivel.

60 In order to seal the pit in such manner as to avoid the free escape of gases and vapors from the oil-bearing stratum and pit to the shaft or tunnel, a sealing member 36 is provided at the mouth of the pit for closing the same (see Fig. 6 for details). This member is provided with the necessary openings for (1) the pipes 37 which reach to the bottom of the pit for withdrawing the liquid hydrocarbons drained to the same; (2) the water pipe 38, joined to the flexible conduit connected to the end of the shaft; (3) the screws extending through the platform to the bottom of the pit; and (4) the pipe 39 for withdrawing the gases and vapors accumulating in the pit and the oil-bearing stratum.

65 Figs. 7 and 8 show a preferred form of abrasive-cutting means. The main member is made up of segments of suitable length which can be attached to one another in any appropriate manner, such as by screwing into one another. This member or rod has a hollow opening 40 extending throughout the length of the same for the passage of fluid mediums. An abrasive outer covering 41, fitting tightly upon the inner cylindrical sleeve 42, fits securely about the main portion of the member. In order that the abrasive sleeve may not slide upon the member, it is preferred that the member be provided with a recessed portion 43, which is adapted to contain the shoulder 44 forming a part of the cylindrical sleeve.

70 In Figs. 3 and 4 are shown systems of oil mining according to the present invention. Fig. 3 shows a tunnel extending above the oil-bearing stratum. A plurality of pits 45, 46, 47, 48, 49 and 50 are sunk at intervals along the bottom of the tunnel. Channels may then be cut laterally from these pits in such manner that all of them are substantially parallel or in alignment with one another. A plurality of such tunnels may be dug in a given project, all of them being parallel or 125 in alignment with one another; or, indeed, they may be made to intersect. The same may of course be true of the channels.

75 Fig. 4 shows a modified mining system according to which lateral channels are cut 130

through the oil-bearing stratum from a single shaft and pit 51 substantially perpendicular to one another. This is the preferred system of operation when working only from a single shaft and pit. However, as in the tunnel system just described, a plurality of such single shafts may be dug in a given project. The channels may be parallel, perpendicular, or in alignment with one another; or, indeed, they may be made to intersect.

10 The operation of the above described apparatus is as follows:

After the shaft or tunnel 10 has been dug (Fig. 1) and the pit 13 has been sunk in the bottom thereof, a hole 52 (Fig. 2) is bored through or just above the oil-bearing stratum in any well known manner. The abrasive-cutting means 34 is then pushed into this bored hole. This is accomplished by placing 15 segment on segment, somewhat similar to the well known procedure of boring lateral holes such as indicated. After a sufficient length 20 of abrasive-cutting means have been inserted into the hole, the near end thereof is attached to the shaft 15 by means of the connection 33.

The pulley-sheave 18 is set in motion by means of the rope or belt 19 connected to an engine (not shown). As the abrasive-cutting means 34 is rotated, it gradually cuts or eats 30 its way down through the oil-bearing stratum to form the channel 53. No additional downward force is applied to the abrasive-cutting member other than that supplied by its own weight. In other words, the cutting member 35 lies freely in the channel as it rotates. If the member should cut deeper at one end than at the other, the platform 14 may be suitably raised or lowered—as desired, to make a straight channel. For example, if the member 40 should cut too deep next to the pit, the platform can be held in a stationary position until the extreme end of the member has cut down to a corresponding depth; or, if the reverse condition obtains—that is, the member 45 has cut too deep at its extreme end, the platform is lowered into the pit more rapidly.

As the channel is cut through the oil-bearing stratum, the platform 14 is gradually lowered. This is accomplished by appropriately turning the screws 29 and 30 from the shaft or tunnel. In its upward and downward movements, the platform slides along the guide posts 20, 21, 22 and 23. The oil and other liquids employed are drained to the pit 13, from which they are withdrawn to the surface by means of the pipes 37.

Instead of making use of an abrasive sleeve 41, resort may be had to passing a granular abrasive material through the hollow opening 40 in a liquid vehicle, such as water. The abrasive material, together with the liquid carrier, finds its way to the outer and extreme end of the abrasive-cutting member 34, after which it flows into the channel and back toward the pit. As the member 34 revolves, it

pushes the abrasive granular material between itself and the bottom of the channel. An abrasive-cutting action is thereupon set up which gradually cuts or eats down into the oil-bearing stratum. New granular abrasive material, together with its liquid carrier, is continuously, or at frequent intervals, fed through the center of the cutting member, so that new and effective abrasive material is constantly added beneath the revolving member. In this manner, the channel may be 70 finally cut through the entire oil-bearing stratum. Of course, it is apparent that the abrasive sleeve 41 might also be used in conjunction with the use of granular abrasive material applied as just indicated.

The powdered grindings obtained in cutting a channel are washed back into the bottom of the pit. This is accomplished by forcing a liquid medium, such as water or oil, through the pipe 38, the flexible conduit 35, the hollow shaft 15 and the hole 40 within the revolving member 34. This liquid makes its exit at the extreme end of the member 34, and gradually flows back through the channel, picking up the grindings, and is ultimately deposited in the bottom of the pit.

If the system of mining illustrated in Fig. 3 is followed, a plurality of channels are cut from each sunken pit. The pits may be 95 connected in such manner that the collected oils and liquids may be flowed to one single pit from which they are drawn to the surface. On the other hand, if the system of mining illustrated in Fig. 4 is followed, a 100 plurality of channels are cut through the oil-bearing stratum from but one pit in each shaft. The liquid petroleum and water gradually gathers in the pit 51 from which it may be removed as just indicated.

To avoid free escape of the gases and vapors into the shaft or tunnel, the seal 36 is advantageously placed over the mouth of the pit in such manner as to close the pit while at the same time sealing the shaft or tunnel from the oil-bearing stratum. Any gases or vapors that accumulate below this seal, in the pit and channels, are appropriately withdrawn through the escape conduit 39.

115 I claim:

1. An improved apparatus for cutting drainage channels through an oil-bearing stratum comprising an elongated abrasive member adapted to lie lengthwise of the channel to be cut, means for revolving said member around its longitudinal axis, the ratio of the diameter to the length of said member being such that it rests substantially freely in the channel and exerts no downward force other than that supplied by its own weight.

2. An improved apparatus for cutting drainage channels through an oil-bearing stratum comprising an elongated abrasive member adapted to lie lengthwise of the

channel to be cut, said member being hollow and provided with means for flowing a medium therethrough and out of its far end, means for revolving said member around its longitudinal axis, the ratio of the diameter to the length of said member being such that it rests substantially freely in the channel and exerts no downward force other than that supplied by its own weight.

10 In testimony whereof I affix my signature.
JOHN L. RICH.
